ARTIFICIAL TOOTH

John B. La Due and Jacob A. Saffir, Chicago, Ill.

Application December 9, 1938, Serial No. 244,851

3 Claims.

(Cl. 32—8)

Our invention relates to improvements in artificial teeth, and has to do, more particularly, with the occlusal and masticating surfaces of posterior teeth intended for the replacement of those natural teeth known as molars and bicuspids.

In the last decade, much thought and research has been devoted to the development of a more satisfactory artificial tooth construction for the replacement of natural molars and bicuspids, and a number of posterior-tooth designs have evolved. While, from the standpoint of appearance, these suggested structures vary widely—in point of functional principle, each classifies itself into one of two fundamentally distinct types, as follows:

(A) Posterior teeth in which the occlusal surfaces lie in a single flat or substantially flat plane common to all teeth of the denture, hence are capable of description as "geometrically cuspless;" and

(B) Posterior teeth the occlusal surfaces of which do not lie in a substantially flat plane but include acclivous and declivous portions which function in a manner similar to the cusps of natural teeth and positively induce separative jaw movements during masticating excursions of the mandible.

Our invention pertains to teeth of the class "A" above defined, and has, for its primary object, the attainment therein of a degree of masticating efficiency so effective as to render such "geometrically cuspless" teeth equal or superior to "cusped" teeth in this respect.

Viewed from another angle, our invention may be said to have, as a salient object thereof, the reduction and uniform distribution of stress and effort required for mastication. Corollarily, the individual equipped with such teeth is less subject to mandibular fatigue, the possibility of trauma due to displacement or breakage of denture parts is greatly reduced, and the division of food into finer particles is facilitated.

It is another object of our invention to provide a masticating face for posterior replacement teeth which, by its inherent freedom from "blind" cavities or culs-de-sac, has far less tendency to become clogged with impacted food. This feature of advantage, while primarily adding to the user's comfort and oral hygiene, also evidences itself in more rapid and thorough food mastication.

Considered from the standpoint of the technicians who construct and fit dental restorations to the individual mouth, our invention has another important feature of advantage in that it provides a tooth construction which is "adapt-

able." Not only are the occlusal faces of denture-mounted teeth embodying our invention susceptible of grinding to proper occlusal fit with respect to the facial curvature of the teeth which oppose them, but the pattern of the occlusal surfaces of our type of tooth is such that especial alinement of the opposing maxillary and mandibular teeth of a denture is not so essential to insure either occlusal balance or efficient mastication.

Finally, it is an object of our invention to provide an artificial posterior tooth structure which can be manufactured inexpensively in a wide range of stock sizes and shapes and which may be suitably sculptured on its buccal and lingual faces to closely simulate the natural tooth.

Further objects, and objects relating to details and economies of manufacture, installation and use will readily appear from the detailed description to follow. We accomplish the objects of our invention by the concepts set forth in the following specification. Our invention is clearly defined by the appended claims. Preferred embodiments of our invention are illustrated in the accompanying drawings forming a part of this specification, in which:

Figure 1 is an enlarged view, in side elevation, of posterior denture portions provided with four maxillary and four mandibular teeth embodying our invention, said view disclosing the lingual spillways provided in said teeth;

Fig. 2 is a bottom plan view of the four maxillary teeth of said denture;

Fig. 3 is a top plan view of the four mandibular teeth of said denture;

Fig. 4 is a transverse sectional view of a pair of such denture portions assembled as parts of maxillary and mandibular "plates," the view being taken on the line 4—4 of Fig. 1, but drawn to a somewhat smaller scale.

Fig. 5 is an enlarged plan view of four maxillary or mandibular posterior teeth constituting modified embodiments of our invention; and

Fig. 6 is a greatly enlarged diagrammatic view of a maxillary and a mandibular molar of the form illustrated in Fig. 5, said view depicting a secondary triturating association which characterizes such teeth during mandibular excursion.

Like reference numerals refer to like parts throughout the several views.

Structurally considered, our invention finds embodiment in a "geometrically cuspless" artificial molar or bicuspid the entire occlusal portion of which lies in a substantially flat plane

and is comprised by a boss located centrally with respect to the tooth and a marginal upstanding wall at the periphery of the tooth, substantially encircling said central block and defining a moat-like canal which holds larger particles of food to the masticating surfaces while directing discharge of smaller particles. Functionally considered, such a construction embodied in an appropriate maxillary and mandibular denture distinguishes itself from heretofore-contemplated tooth structures in that the masticating operation is dual, embracing two distinct food-communuting steps which co-operate during masticating excursions of the mandible. As these two operatively-distinguished steps contribute to effect the reduction of a bolus of food to a homogeneous, relatively smooth, saliva-saturated plastic mass suitable for facile digestion, they may be defined as the "shearing step" and the "trituration step;" the former tearing or shredding the food into small particles, and the latter grinding the small particles in a manner similar to that characterizing the use of a mortar and pestle. From the foregoing explanation it may be readily appreciated that we have developed a facial structure, for artificial posterior teeth, which, in point of view of oral food processing, compares favorably with the effectiveness of natural molars and bicuspids, yet is basically distinguished therefrom, structurally, in that interdigititation of cusps is entirely precluded.

More specifically, we refer now to Figs. 1 to 4 of the accompanying drawings in which is illustrated a simple form of artificial tooth construction embodying the basic concepts of our invention. Reference to Figs. 1 and 4 reveals the "planar" disposition of the occlusal surfaces of these teeth. In this connection, it is to be pointed out that the expression "planar" is used in its broad sense and includes not only an absolutely geometrically plane surface, but a slightly spherical surface as well, it being well known that natural teeth generally, occlude spherically on radii which vary, in different individuals, from 2 to 15 inches.

Fig. 1 is a lingual view of eight teeth embodying our invention and secured to mandibular and maxillary denture portions A, B, by any suitable means (not shown). Fig. 3 is a top plan view of the first bicuspid C, second bicuspid D, first molar E and second molar F of one side of the mandibular denture portion A illustrated in Figs. 1 and 4 jointly. Fig. 2 is a bottom plan view of the first bicuspid G, second bicuspid H, first molar I and second molar J of the coacting side of the maxillary denture portion B illustrated in Figs. 1 and 4 jointly.

While, in actual practice, the molars E, F, I and J as well as the bicuspids C, D, G and H may vary considerably in relative size, proportion, placement and general appearance, depending upon the jaw structure of the individual mouth, for the explanation of the basic concepts of an invention each bicuspid may be considered identical to its neighbors, as may the molars. Each bicuspid comprises a body portion 10 provided with any suitable means (not shown) for securing it to the denture mounting A or B, a boss 11 extending integrally upwardly from the tooth body and terminating in a substantially flat triturating surface 11a disposed in the common occlusal plane for the teeth of the denture. Substantially encircling the triturating boss or block 11, and extending upwardly from the periphery of the tooth body 10, is a relatively nar-

row marginal wall 12 which terminates in a flat edge 12a disposed in the common occlusal plane for the denture. There is thus defined, between said triturating block 11 and the marginal wall 12, a moat-like canal 13 which co-operates with the occlusal portions 11, 12 of the tooth in several functional particulars later to be explained. This canal communicates with the lingual side of the tooth body through lingual spillways 14, 15.

The structure of each molar E, F, I and J is generally similar to that of the bicuspids described. These are each comprised by a body portion 20, a central triturating block 21 and a marginal wall 22 extending upwardly from the tooth body. The surfaces 21a and 22a of the molars lie in a plane common to all teeth of the denture. A moat-like canal 23 surrounds the triturating block 21 and communicates with the lingual and buccal sides of the teeth through spillways 24 and 25 cut through the marginal wall 22.

Assembled as occlusal maxillary and mandibular elements of a denture, teeth of this construction function to comminute the bolus of food by two distinct methods. The rather sharply occluding edges of the maxillary and mandibular elements 11, 21 and 12, 22, as they traverse the canals 13, 23 of opposing teeth, direct large food particles thereinto and, being so directed, these particles are "sheared" as the teeth continue the traversing movement induced by masticating excursion of the mandible. The end-for-end tumbling of the larger food particles into these canals 13 and 23 is not difficult to envision from study of the several Figures 1 through 4.

Further subdivision of the food particles produced by this "shearing" action is effected between the maxillary and mandibular triturating block surfaces 11a and 21a as these move relative to each other in close proximity. This final division or "trituration" of food into particles of considerable fineness is analogous to that accomplished by the use of a conventional mortar and pestle. The thus-detrited food particles, particularly when moistened to fluidity with normal salivary secretion administered by the tongue, are readily swept into the canals 13 and 23 from whence they reach the mouth proper through the various spillways 14, 15, 24, 25 cut through the marginal walls 12, 22 and preferably extended slightly into the body portions 10 and 20 of the teeth.

Reference to Fig. 1 of the drawings, which discloses the mandibular teeth in a protrusive occlusal association with respect to the maxillaries, clearly demonstrates that the "shearing" function of teeth of this type need not occur only between teeth which are axially alined; a bicuspid being capable of thus coacting with a molar. More than this, though to a far lesser extent, some trituration may take place, during extremes of mandibular excursion, between the marginal wall portions of the occlusal face and the central triturating block of subjacent or superjacent teeth, the marginal wall serving somewhat in the manner of a pestle against the central block as a mortar. In teeth of the basic structural form illustrated in Figs. 2 and 3, this supplemental triturating action is relatively slight as compared with that effected between the central blocks per se. However, by a modification of marginal wall configuration, this supplemental action may be materially increased, as will appear from the description to follow and relating to the modified

embodiment of the invention disclosed in Figs. 5 and 6.

From the foregoing description of the structure and functional operation of the teeth illustrated in Figs. 1 through 4, the basic principles and advantages of our invention should be readily appreciated. The teeth are geometrically cuspless, all occlusal surfaces thereof lying in a flat or substantially flat surface common to all teeth of the denture. Cuspal interdigitation with attendant localized stresses tending to displace the tooth supports is impossible; fatigue and trauma are reduced to an irreducible minimum; and food mastication is efficient to a degree comparable with that achieved by perfectly arranged natural teeth. Due to the generally open pattern inherent to our tooth design, impaction of food in such teeth is not likely to occur, nor is there likelihood of the creation of a jaw-locking vacuum between the occlusal surfaces thereof. Especially advantageous is the simplicity of the design and the correspondingly reduced cost at which such teeth may be manufactured and installed by the reconstructionist. Any suitable buccal and lingual carvings may be applied to our teeth to cooperate with that inherent to the spillway formations 14, 15, 24 or 25 and to disguise the fact of dental restoration. Likewise, the shape and configuration of the occlusal portions 11, 12, 21 and 22 of these teeth may be varied considerably without departing from the basic concepts of our invention. These variations in non-functional configuration are matters primarily of artistry and do not relate materially to the functional principles with which the present invention is concerned.

In Fig. 5 we have disclosed a modified form of tooth structure constituting another embodiment of our invention. Here the central triturating block 31 of the bicuspids K, L, is supplemented by widened occlusal portions 32b, 32c at the buccal and lingual sides, respectively, of the marginal wall 32. The mesial and distal edges 32a of the wall 32 remain narrow, as in the embodiment disclosed in Figs. 2 and 3. A moat-like food-directing canal 33 separates the central triturating block 31 from the marginal wall 32, as in the previously described form of tooth, and lingual spillways 34, 35 facilitate discharge of properly masticated food therefrom.

The molars M, N, which correspond in structure to these bicuspids, each include a relatively elongate central triturating block 41 which is functionally supplemented by widened occlusal portions 42b, 42c, 42d and 42e of the marginal wall 42. The mesial and distal edges 42a of the wall 42, like those 32a of the bicuspids, remain narrow. The characteristic moat-like food-directing canal 43 separates the central triturating block 41 from the marginal wall 42 and discharge of properly masticated food particles is facilitated by communicating lingual and buccal spillways 44 and 45. The several occlusal faces 31a, 32a, 32b, 32c, 41a, 42a, 42b, 42c, 42d and 42e of these teeth all lie in a common flat or slightly spherical plane and function in the same general manner as those 11a, 12a, 21a, 22a of the first-described teeth. Due, however, to the broadening of buccal and lingual portions of the marginal walls 32 and 42, a very material supplementation of triturating action is afforded with teeth of this modified form.

For a graphical depiction of this supplemented triturative capacity, reference is made to Fig. 6 in which the occlusal surfaces of two molars X

and Y are shown in a laterally displaced relationship occurring during mandibular excursion. These molars X and Y are of the same general form as those M and N of Fig. 5. The maxillary molar X is provided with a central triturating surface X-1a, mesio-lingual triturating surface X-2b, disto-lingual triturating surface X-2c, mesio-buccal triturating surface X-2d and disto-buccal triturating surface X-2e, as well as mesial and distal marginal edges X-2a. The mandibular molar Y is identical in form and includes corresponding triturating surfaces Y-1a, Y-2b, Y-2c, Y-2d and Y-2e, as well as mesial and distal marginal edges Y-2a. A food canal extends about the central triturating block of each tooth and is designated X-3 of the maxillary and Y-3 of the mandibular molar. The canal X-3 is provided with a lingual spillway X-4 and a buccal spillway X-5, and the canal Y-3 is provided with corresponding lingual and buccal spillways Y-4 and Y-5, respectively.

A clear understanding of primary trituration afforded between the central occlusal surfaces X-1a and Y-1a of these teeth can be gained from the disclosures in Figs. 1 and 4. As the teeth X and Y move from this position of central alinement to the lateral position depicted in Fig. 6, food trapped in the canals X-3 and Y-3 is chopped by the shearing action of canal-defining edges of the occlusal portions Y-2b, Y-2c across 30 the proximate edge of the central occlusal portion X-1a, and by the canal-defining edges of the occlusal portions X-2d, X-2e across the proximate edge of the central occlusal portion Y-1a. While some supplemental shearing is effected by the 35 marginal wall portions X-2a and Y-2a in their traversal of each other and portions of the broader occlusal surfaces of these teeth, these function rather to force the food along the canals Y-3 and X-3 and through the spillways Y-4 and 40 X-5 during the lateral cycle which terminates in the dental relationship depicted in Fig. 6. From this description it will be readily appreciated that approach of the teeth X and Y to the offset position shown in Fig. 6, effects several 45 functions important to mastication.

1. Larger food particles bridging the canals X-3 and Y-3 are subdivided by shearing.

2. Food in the canals X-3 and Y-3 is shifted about, particularly toward the spillways Y-4 and 50 X-5.

3. Food urged through the spillway Y-4 is directed upon the triturating surfaces X-1a, Y-2b, Y-2c.

4. Fine particles of food are urged to discharge 55 from the teeth through the spillway X-5.

5. Supplemental trituration is effected between the surfaces X-1a and Y-2b, Y-2c; and X-2d, X-2e and Y-1a.

During the return cycle of movement to alined 60 occlusion the following salient component masticating functions occur.

1. Trituration constituting a continuance of that (5) above occurs.

2. Food in the canals X-3 and Y-3 is shifted 65 about into positions where shearing of larger particles, and trituration of smaller particles, is assured.

3. Spillways Y-4 and X-5 become intrusion 70 ducts for the portion of the food which remains for processing by the teeth, spillways Y-5 and X-4 becoming avenues of escape for properly subdivided food.

4. Shearing of larger food particles occurs between the proximate edges of the occlusal por- 75

tions $X-2b-Y-2b$, $X-2c-Y-2c$, $X-2d-Y-2d$, $X-2e-Y-2e$, $X-1a-Y-1a$, to a lesser extent, $X-2a-Y-2a$, and various combinations of these "X"-exponented and "Y"-exponented occlusal portions, depending upon the directional characteristics of the mandibular excursion.

5. Primary trituration at the terminal portion of this return cycle is effected between the trituting surfaces $X-1a-Y-1a$, $X-2b-Y-2b$, $X-2c-Y-2c$, $X-2d-Y-2d$, and $X-2e-Y-2e$.

Lateral mandibular excursion in mastication being generally symmetrical, the "return" cycle just described "follows through" to a position of displacement which is the reverse of that disclosed in Fig. 6, during which functional operations generally corresponding to those first described occur. Likewise, return movement from this reversed position embodies functional effects similar to the return movement from the first cycle. To describe these corresponding cycles is, therefore, unnecessary.

While we have endeavored to point out salient functional effects normal to mastication with teeth of the structural form illustrated, it may be readily appreciated that, due to the intricacy and variation of mandibular movements comprising mastication as practiced by each individual, it would be impossible to discuss all the functional relationships occurring with our novel teeth. Although mandibular masticating movements embrace protrusive, retrusive, bi-lateral and separative components in a myriad of combinations, the functional effects of teeth embodying our invention have been set forth with sufficient fundamental particularity to establish primary distinctions which characterize that invention. Inasmuch as the molar construction illustrated in Figs. 5 and 6 is, in a sense, a twinning of the bicuspid construction illustrated in Fig. 5 and a common functional similarity underlies both the single and "twinned" structures, an understanding of the operation of this bicuspid structure will occur to those skilled in the art without further detailed explanation.

45 From the foregoing description of the structural and functional concepts which characterize our invention it will be obvious that considerable variation in size, configuration and arrangement is permissible without departing from these concepts. While we have disclosed our invention as embodied in a full restoration of the natural posterior teeth, obviously the invention is applicable to partial restorations supported by crown, plate or bridge. Ornamentation of lingual and buccal surfaces of such teeth is also, naturally, contemplated. While we have disclosed only two distinct forms of occlusal patterns which fulfill the structural and functional requirements of our concepts, it is self-evident that other patterns of greater or lesser intricacy might be employed without a departure from essential principles. These and other variants will readily occur to persons skilled in the art and such changes are contemplated as optional practice of our invention. We, therefore, claim our invention broadly, as indicated by the following claims.

What we claim is:

1. An artificial tooth of the geometrically cuspless type the occlusal surfaces of which all lie in

a single, substantially flat plane, comprising: a body portion adapted for anchorage to a tooth mounting member, said body portion terminating at a considerable distance from the occlusal plane of the tooth, a substantially continuous annular wall extending occlusally from the periphery of said body portion and terminating as the marginal occlusal edge of the tooth, a relatively broad, centrally-located boss extending occlusally from said body portion and constituting a broad food trituting block the milling surface of which is disposed in said common occlusal plane, and an annular canal isolating said central and marginal occlusal portions and constituting a magazine for the reception and application of food particles to said trituting block.

2. An artificial tooth of the geometrically cuspless type the occlusal surfaces of which all lie in a single, substantially flat plane, comprising: a body portion adapted for anchorage to a tooth mounting member, said body portion terminating at a considerable distance from the occlusal plane of the tooth, a boss integral with said body portion and extending occlusally from the central portion thereof to constitute a broad food trituting block the milling surface of which is disposed in said common occlusal plane, a marginal wall extending integrally upwardly from the periphery of said body portion and terminating in an occlusal edge substantially encircling said central trituting block, a supplemental trituting block intermediate said marginal occlusal edge and said central trituting block, said supplemental trituting block having its milling surface lying in said common occlusal plane, and an annular canal isolating said central occlusal block from said supplemental block and marginal wall and constituting a magazine for the reception and application of food particles to said trituting blocks.

3. An artificial tooth of the geometrically cuspless type the occlusal surfaces of which all lie in a single, substantially flat plane, comprising: a body portion adapted for anchorage to a tooth mounting member, said body portion terminating at a considerable distance from the occlusal plane of the tooth, a boss integral with said body portion and extending occlusally from the central portion thereof to constitute a broad food trituting block the milling surface of which is disposed in said common occlusal plane, a marginal wall extending integrally upwardly from the periphery of said body portion and terminating in an occlusal edge substantially encircling said central trituting block, a supplemental trituting block inbuilt into a lingual portion of said marginal wall, a supplemental trituting block inbuilt into a buccal portion of said marginal wall, each of said supplemental trituting blocks having its milling surface disposed in said common occlusal plane and constituting extensions of the occlusal surface of said marginal wall, and an annular canal isolating said central occlusal block from said other occlusal portions of said tooth and constituting a magazine for the reception and application of food particles to said trituting blocks.
